UNITED STATES PATENT OFFICE.

ROBERT M. HANDLY, OF METZ, MISSOURI.

DESIGN FOR A FENCE-POST.

SPECIFICATION forming part of Design No. 31,091, dated June 27, 1899.

Application filed May 27, 1899. Serial No. 718,603. Term of patent 7 years.

To all whom it may concern:

Be it known that I, ROBERT M. HANDLY, of Metz, Vernon county, Missouri, have invented and produced a new and useful Design for 5 Fence-Posts, of which the following is a full, clear, and exact description, reference being had to the accompanying drawing, forming part thereof.

My invention relates to a new and useful de-
10 sign for fence-posts.

In the accompanying drawing, which represents a perspective view of a fence-post, showing my new design, the leading or material feature consists in the elongated body portion, 15 terminating at its lower end in a branched or forked foot portion, the branches or forks of said foot portion extending substantially parallel with each other and with the body portion.

20 Minor features of my design reside in the arched portion, connecting the upper end of one of the branches or forks with the other and with the body portion A; also, in the series of hole-like figures in the body portion and 25 in the hole-like figures of the branches or forks, the figures of one branch or fork being directly opposite those of the other. This post

is adapted to receive between said branches or forks a rock-anchor (not shown) provided with holes registering with the holes of said 30 branches or forks in order that bolts may be utilized to secure the post and rock reliably together.

Referring to the drawing in detail, 1 designates the body of the post, and 2 the series of 35 hole-like figures thereof.

3 designates the foot portion, one of the branches or forks thereof being identified by the number 4 and the other by the number 5.

6 designates the arched portion, connecting 40 the upper ends of the branches or forks with the lower end of the body portion, and 7 designates the hole-like figures of the said branches or forks.

What I claim is—

45 The design for a fence-post, as herein shown and described.

In testimony whereof I affix my signature in the presence of two witnesses.

ROBERT M. HANDLY.
